UNITED STATES PATENT OFFICE

JOHN C. BAKER, OF NUTLEY, NEW JERSEY, ASSIGNOR TO WALLACE & TIERNAN PRODUCTS, INC., OF BELLEVILLE, NEW JERSEY, A CORPORATION OF NEW JERSEY

RUBBER PRINTING PLATE

Application filed March 24, 1928. Serial No. 264,329.

This invention relates generally to printing and has particular reference to the making of rubber printing plates.

One of the objects of this invention is to provide a method of making metal-backed rubber printing plates which are accurate reproduction in all essential particulars of an engraved or etched die or master plate.

Another object of the invention is to provide improvements in known apparatus for producing rubber printing plates which, in addition to other characteristics, will be of the same thickness as the master plate or die used in making the plates.

Other objects and advantages will be apparent from the disclosures hereinafter set forth, in connection with the drawings which accompany and form a part of this specification.

In said drawings:

Fig. 1 shows a suitable press and associated elements for performing one of the early steps involved in the making of metal-backed rubber printing plates.

Fig. 2 is a cross section illustrating a result of the operation of the apparatus of Fig. 1.

Figs. 3 and 4 illustrate the apparatus and method of producing a lead lined, rigid mold upon the master plate.

Fig. 5 shows how the master plate is preferably removed from the lead lined mold and Fig. 6 is a cross section through the lead lined mold from which the master plate has been removed.

Fig. 7 shows the essential features of the new apparatus which comprises a vulcanizing press which is more or less conventionally represented.

Fig. 8 shows how the mold may, if desired, be stripped from the finished rubber printing plate.

Rubber printing plates, or rubber faced printing plates, have been used for many years for certain kinds of printing. However, a more general use, particularly for fine art printing, has been prevented by certain difficulties which have imposed definite limitations. One of the most important of these limiting factors is that it has been im-

possible to get accurate alignment or registration when printing from such plates, due to unavoidable variations between them and what are, for convenience, usually referred to herein as the dies or master plates. Such dies or plates are produced in various ways, such as by casting, etching or engraving and are true to the dimensions of the picture or design which is to be produced.

The variations between the rubber plates of the prior art and the master plates arise partly from the fact that the molds in which the rubber is formed to give the printing design, do not expand at the same rate as the rubber in vulcanizing, and when the finished plates are removed from the vulcanizing mold and cooled, it is found that the rubber has shrunk so that the plates are smaller than the original, and that the various elements of the design or picture are out of their correct relative positions.

In prior manufactures the rubber plates have, after vulcanization, been mounted on metal or wooden plates so that they can be carried in a printing press. It has been appreciated that this attaching operation might be made a part of the vulcanizing operation, and that if the rubber plates could be vulcanized on metal backing plates shrinking and other harmful variations from the master plates might largely be prevented. However, in prior manufactures it has been found difficult to effect such vulcanization on the backing because of the nature of the molds employed and the methods of using them in manufacturing. While attempts have been made along the line indicated, they have, so far as known, been unsatisfactory because of the high percentage of damaged or defective plates.

It has now been discovered how these difficulties can be overcome and an accurate undamaged plate produced which is vulcanized to a metal backing of sufficient stiffness to prevent any subsequent shrinking of the rubber or displacement of the rubber.

Stated in general terms the new way of manufacturing such plates comprises the use of lead lined, special molds for the rubber forming and vulcanizing operations. Such a

mold is produced by first copying in a sheet of lead the outline and surface configuration of a die or master plate. In making the copy the sheet of lead is forced into and over the master plate by pressure.

In order that the lead may faithfully receive all of the details of the master plate, the pressure is applied by any suitable press through a pad of yielding material which is fibrous enough to prevent breaking the pad down too readily, but which will yield sufficiently to cause a satisfactory distribution of the pressure. A pad of dry paper pulp or one composed of sheets of newspaper gives very satisfactory results. Applying the pressure through such a pad forces the lead into all of the details of the die or master plate, thereby effecting a very accurate embossing in the lead of all features of the picture or design. The pressure is then released and the pad removed, leaving the lead pressed into and around the master plate.

A backing is then applied which is rigid and which will hold the design in the lead after the lead is removed from the master plate. For this purpose a material is used which can be poured over the lead sheet and master plate and which will set to a rigid form. A satisfactory material is a mixture of glycerine and litharge or a dental cement. Before starting the pouring operation the master plate, and the adhering lead sheet, is laid on a truly flat surface, and after pouring, and before the material has had time to set, a similar truly flat plate is used to force the material down until this second plate is arrested by stops provided for that purpose. These stops are of such height that sufficient backing material remains behind the lead to give ample rigidity at all points.

After the backing has set, the master plate, with the attached rigid backing, is removed from the supporting and pressure plates. The master plate is then removed, leaving a lead lined mold which is ready for use in molding and vulcanizing rubber plates. In the preferred practice this lead lined mold is not quite as deep as the thickness of the master plate, the reasons for this difference and the way in which it is obtained being hereinafter explained in detail.

The lead lined mold is then placed between relatively movable plates of a vulcanizing press having their faces truly flat and parallel. Either before or after placing the mold in the press, it is supplied with a suitable plastic rubber compound containing the usual or any desired vulcanizing and similar agents, the quantity of the compound being in excess of that required for the finished plate.

A backing plate previously treated to cause adhesion of the rubber is then applied to the compound and the vulcanizing press operated to force that plate toward the mold.

This compacts the compound in all of the de-

tails of the lead lined mold, and extrudes the excess rubber between the top of the mold and the backing plate. Stops between the relatively movable portions of the vulcanizing press arrest that movement at the point where the thickness through the rubber and backing plate is substantially the same as the thickness of the die or master plate used in making the mold. As a result, after the vulcanization is completed the finished rubber plate will be a metal backed rubber reproduction of the master plate in dimensions and all other essential characteristics.

The metal backing plate employed is preferably composed of an alloy of lead and antimony. Such a material has the necessary rigidity to hold the rubber in position, but is nevertheless capable of being formed to offset irregularities or regulate the impression of the printing face. Such a metal or alloy presents difficulties in the way of getting a good adhesion of the rubber and the backing plate, but it has been discovered that if the face of the plate which engages the rubber is washed with a dilute solution containing copper sulphate and copper nitrate a perfect adhesion will result from the molding and vulcanizing operation.

Describing the apparatus and the manufacture more in detail and with reference to the drawings, a book press 10, such as is shown in Fig. 1, may be employed when the sizes of the printing plates required do not necessitate a greater press capacity. In making larger plates a hydraulic or other more powerful press may be employed.

The top surface of the bed 11, and the lower face 12 of the platen 13 of the press should both be flat and substantially parallel.

At the start of the operation the master plate 14 which is to be reproduced is placed face up on the bed of the press. Strips of paper or metal 15 are then placed on the bed and around the master plate and a sheet 16 of lead laid over the face of the master plate. Superimposed on the sheet of lead is a yielding pad 17 which is preferably of a somewhat fibrous nature, a suitable material being dry paper pulp or a number of plies of newsprint paper.

The press 10 is then operated to apply pressure through the pad 17 to force the lead 16 into and over the master plate and into contact with the strips 15 around the master plate 14. Stops 18 serve to prevent movement of the platen far enough to have a destructive effect upon the lead. As a result of the press operation the lead sheet is embossed and shaped to the master plate as illustrated in Fig. 2. Examination of Fig. 2 will show that the side portions or extensions 16' of the lead are, owing to the effect of the strips 15, parallel to and slightly above the back of the master plate.

The master plate, with the adhering lead,

is then laid on a truly flat surface 18, Fig. 3, of a block or plate 19, with the lead covered face up, after which a backing for the lead is applied. This backing is preferably of a material which can be applied in fluid condition and which will set readily, but which will also be sufficiently rigid and strong to stand pressing and vulcanizing operations. This material may be varied, but a mixture of glycerine and litharge or dental cement has been found very satisfactory. Before starting the pouring operation it may be necessary to support the portions 16' of the lead sheet by strips similar to the strips 15 used in the matrix forming press 10, as it is desirable that the portions 16' be maintained in substantially the positions given them in the press.

As soon as the pouring is completed and before the backing material has begun to set, a plate 21 (Fig. 4) accurately machined to give a truly flat surface is laid on the material and forced down by gravity, assisted by a hand pressure or by a weight 22, if desired, until arrested by stops 23. These stops might be permanently attached to the block 19 when a number of molds of the same depth are to be prepared or they may be interchangeable to suit varying conditions. They must always be of sufficient height to provide for a backing of sufficient thickness to properly support the lead.

After the backing has set, the master plate 14 and the backed lead sheet are removed from the press and the master plate then removed. This is accomplished or assisted by directing a jet of air 24 around the edge of the master plate as illustrated in Fig. 5. This leaves a lead lined mold 25, illustrated in Fig. 6, which is slightly less in depth than the thickness or height of the master plate, and which contains a true copy of the master plate.

The mold is then supplied with rubber compound in plastic condition as shown at 27 in Fig. 7, the quantity of compound being preferably considerably in excess of the quantity of rubber which will be found in the finished article. A backing plate 28 is then laid on the compound and the assembly introduced between the relatively movable elements 31 and 32 of a vulcanizing press of a known type but which have their opposing faces truly flat and parallel when closed. The press is next operated to mold the rubber and vulcanize it.

The relative movement of the elements 31 and 32 compresses the rubber plastic in the mold and extrudes the excess between the edges 34 (Figs. 6 and 7) of the mold and the backing plate 28. The strips 15 (Fig. 1) were used so as to provide a clearance between the plate and mold which, while preventing too free an extrusion, will permit the excess rubber to escape. The extruded portions 35 of the rubber are later trimmed off.

In order to limit the relative movements of the press members 31 and 32 to produce a mounted rubber plate of the desired thickness, stops 36 are employed. These stops should preferably be of the same height as the stops 23 (Fig. 4) in the mold forming press, if the finished plate desired is to have the same thickness as the master plate. If a finished plate of a thickness different from that of the master plate is desired the stops 36 should be adjusted accordingly.

The molds are not re-used and may be stripped from the finished plates in the manner illustrated in Fig. 8 by means of the sheet of lead 16.

The composition of the metal backing plate and the manner in which it is prepared to secure firm adhesion of the rubber to the metal were explained above, and repetition is unnecessary.

While the lead is, on the whole, the most satisfactory for the matrix making, it is not the desire to be limited to that metal. Any soft metal or alloy may be used and are considered as being equivalents coming within this invention.

From all of the foregoing it is apparent that accurate rubber printing plates can be produced with a minimum amount of equipment and at a very low cost. Plates produced in the manner described give very accurate registration of impressions, and the work produced by them, particularly in color printing, presents a much better appearance than has heretofore been obtained from rubber plates.

While the method and apparatus set forth are highly satisfactory in all respects, it is obvious that changes in the apparatus and variations in the separate steps or sequence of steps may be made, all of which come within the scope of the claims which follow.

What is claimed is:

1. A method of making metal-backed rubber printing plates which comprises first making a lead-lined mold for the printing face of the plate, supplying to the mold a quantity of unvulcanized rubber compound, in plastic condition, compressing the compound between the mold and a rigid backing plate treated to cause adhesion of the rubber during vulcanization, said compression effecting the molding and causing extrusion of the excess compound, and vulcanizing the rubber while it is compressed between the mold and the backing plate.

2. The method of making printing plates which comprises applying a sheet of lead to the engraved or etched face of a master plate and applying pressure to force the lead against and in all parts of said face, casting a backing on the lead sheet while in engagement with said face in such a way as to produce a lead-lined mold having its front and

back parallel, separating the mold and plate, applying vulcanizable rubber plastic to the lead-lined mold in excess of the amount required to form a printing plate of the desired thickness, applying a previously prepared metal backing plate to said plastic, forcing said backing plate and the mold together to mold the rubber and applying vulcanizing heat to vulcanize the rubber and cause it to adhere to the backing plate, and then removing the mold.

3. The method of making printing plates which comprises copying a design from an engraved or etched plate by forcing a lead plate into all parts of the engraved or etched surface of said plate, pouring on said lead plate while it is in such contact with the engraved or etched plate a cement in fluid condition, applying sufficient pressure to the cement while in fluid condition to force the cement into close contact with all portions of the lead sheet and then allowing the cement to set, removing the engraved or etched plate from contact with the lead plate, applying unvulcanized rubber in plastic condition to the exposed face of the lead plate, and applying molding pressure and vulcanizing heat to said rubber.

4. A method of making printing plates which comprises embossing in a lead sheet, from a master plate, a reversed copy of the matter on the etched or engraved face of the plate, attaching a rigid backing to said sheet in such a way as to produce a lead-lined mold of a depth which is from fifteen to thirty thousandths of an inch less than the total thickness of the master plate, supplying said mold with a quantity of unvulcanized rubber compound in plastic condition in excess of the amount required to fill the mold, applying a backing plate to the supply of compound, said plate having previously been prepared to effect adhesion of the rubber in vulcanizing, and applying pressure and heat sufficient to force the backing plate and mold together to produce a metal-backed rubber printing plate having the same thickness at all points as the master plate.

5. A method of making printing plates which comprises making a lead mold for producing the design on said plates, supplying said mold with a quantity of unvulcanized rubber compound in plastic condition, placing on said supply of compound a backing plate composed of lead and antimony alloy and having the face in contact with the compound previously washed with a solution containing copper sulphate and copper nitrate, and then forcing the backing plate and the mold together to form the printing plate and extrude the excess rubber, and applying heat to vulcanize the formed plate and attach it to the backing plate.

6. A method of making printing plates which comprises placing a sheet of lead on

the engraved or etched face of a master plate, applying sufficient pressure to the sheet of lead through a yielding pad of dry paper pulp to force the lead into and over all portions of said face whereby to emboss in the lead sheet a copy of the matter on said face, casting a backing on said sheet in such a way as to produce a lead-lined mold having the back of the mold parallel with the said face of the master plate and the depth of the mold less than the thickness of the master plate, removing the master plate from the lead-lined mold, supplying the interior of said mold with a quantity of unvulcanized rubber compound, in plastic condition, in excess of the quantity required to fill the mold, placing a backing plate of electrolytic metal on the supply of rubber compound, the face of said plate which is in contact with the compound having previously been washed with a solution containing copper sulphate, and applying pressure and heat sufficient to force the backing and mold together to produce a metal-backed rubber printing plate having the same thickness at all points as the master plate.

7. A method of making molds for rubber printing plates and the like which comprises forming a lead matrix on the engraved face of a master plate in such a way as to copy in the matrix the essential features represented on said face, casting on the back and sides of the matrix a reinforcing back while the matrix is still on the master plate, and applying an air jet around the edges of the master plate to free the plate from the mold.

In testimony whereof I hereto affix my signature.

JOHN C. BAKER.
